(57) **CLAIM**

The ornamental design for a display screen with animated graphical user interface, as shown and described.

DESCRIPTION

FIG. 1 is a front view of a first image in a sequence for a display screen with animated graphical user interface in accordance with the present invention;

FIG. 2 is a front view of a second image thereof;

FIG. 3 is a front view of a third image thereof;

FIG. 4 is a front view of a fourth image thereof;

FIG. 5 is a front view of a fifth image thereof; and,

FIG. 6 is a front view of a sixth image thereof.

The appearance of the animated images transitions sequentially between the images shown in FIGS. 1-6. The process or period in which an image transitions to another forms no part of the claimed design.

The outermost broken line showing of the display screen forms no part of the claimed design. The broken lines showing portions of the graphical user interface, including the text “A66_Lamp2”, “sengled”, “pulse”, and “solo”, an oval, and line across the top of the screen form no part of the claimed design.
